UNITED STATES PATENT OFFICE

167,545

STEIN

Charles C. Smith, Bluefield, Va.

Application April 8, 1952, Serial No. 19,230

Term of patent 14 years

(Cl. D36—8)

To all whom it may concern:

Be it known that I, Charles C. Smith, a citizen of the United States, residing at Bluefield, in the county of Tazewell, and State of Virginia, have invented a new, original, and ornamental Design for a Stein, of which the following is a specification; reference being had to the accompanying drawings, forming a part thereof.

Figure 1 is a perspective view of a stein, showing my new design;

Figure 2 is a perspective view of the stein, but taken from a different point of view;

Figure 3 is a perspective view showing the stein turned approximately 90° about a vertical axis from the position shown in Figure 2.

I claim:

The ornamental design for a stein, as shown.
CHARLES C. SMITH.
